(57) CLAIM

I claim the ornamental design for a cigarette with stopping point indicator, as shown and described.

DESCRIPTION

FIG. 1 is a perspective view of a cigarette with stopping point indicator, showing my new design;

FIG. 2 is a front elevational view thereof, the left side elevational view being identical thereto;

FIG. 3 is a top plan view thereof; and,

FIG. 4 is a bottom plan view thereof.

The rear and right side elevational views are a mirror image to the FIG. 2 drawing view.
